REVERSIBLE RATCHET SOCKET WRENCH HEAD
Louis J. Lenci, Jr., 165 Allison Ave., Cotati, Calif., and
Charles A. Davis, 336 Redwood Ave., Woodacre, Calif.

Filed May 20, 1960, Ser. No. 30,504

7 Claims. (Cl. 81—63)

This invention relates to a novel reversible ratchet socket wrench head.

The primary object of the invention is to provide a more versatile and more efficient heavy-duty wrench head of the kind indicated, which can be used on various types of speed wrenches, such as slide bar, T-bar, extension types, etc., and which is more compact and of unusually small cross-section, so as to be reachable into and operated in confined spaces, and whose rotary component is itself a nut socket or a socket for removable and interchangeable adapter nut sockets of different forms and sizes.

Another object of the invention is the provision of a strong and stress resistant wrench head of the character indicated above whose ratchet mechanism is composed of an unusually small number of simple and rugged parts, such that, because of this and the forms of the parts and their relationships, the parts can be made heavier than usual, so that the mechanism has greater strength and life expectancy.

Other important objects and advantageous features of the invention will be apparent from the following description and the accompanying drawings, wherein, for purposes of illustration only, a specific form of the invention is set forth in detail.

In the drawings:

FIGURE 1 is a top plan view of a wrench incorporating a wrench head in accordance with the present invention;

FIGURE 2 is a side elevation of FIGURE 1, with the wrench head broken away and in section to show the ratchet mechanism;

FIGURE 3 is an enlarged fragmentary longitudinal section taken through the wrench head and an adapter socket;

FIGURE 4 is a fragmentary longitudinal horizontal section taken on the line 4—4 of FIGURE 3, showing the flexible ratchet key or dog in erect intermediate position in full lines, and in deflected release positions in phantom lines;

FIGURE 5 is a view similar to FIGURE 4, showing the ratchet dog moved to a left-hand position for clockwise driving of a nut by the wrench head;

FIGURE 6 is a view like FIGURE 5, showing the ratchet dog moved to a right-hand position for counter-clockwise driving of a nut;

FIGURE 7 is a fragmentary horizontal section taken on the line 7—7 of FIGURE 3;

FIGURE 8 is a horizontal section taken on the line 8—8 of FIGURE 3; and

FIGURE 9 is an open end elevation of an adapter socket.

Referring in detail to the drawings, wherein like numerals designate like parts throughout the several views, the numeral 10 generally designates a wrench having a wrench head 12, in accordance with the invention. The wrench 10 comprises an elongated, preferably solid handle 14 which has a straight flat upper surface 16 and a rearwardly tapering flat undersurface 18, which is transversely rounded, as indicated at 20. The handle 14 is of substantially hourglass shape which endows the same with a rearwardly and longitudinally flaring rear portion 22 which tapers from a narrow waist 24, and a forwardly flaring portion 26, which tapers from the waist 24, and terminates at its forward end in a semi-circular

2

head body 28. The head body 28, as shown in FIGURES 2 and 3, is preferably solid, and is of unusually great cross-section and depth, considering the cross-section of the handle 14 and the overall size of the wrench.

5 The head body 28 is formed therethrough with an axial, smooth, and uniform diameter cylindrical bore 30, having at its upper end a surrounding annular groove 32, and at its lower end a surrounding annular seat 34, formed severally in the upper and lower ends 36 and 38, respectively, of the head body.

10 Rotatably engaged in and relatively closely fitting the bore 30 is a cylindrical ratchet socket rotor 40 which has an enlarged diameter, externally rounded head 42 on its upper end, which turns in the groove 32, and has stop engagement with the head body 28. The socket rotor 40 is longer than the depth of the head body 28 and has a lower end portion 44 which extends below the lower end 38 of the head body. At the location of the annular seat 34 the rotor 40 is formed with a circumferential annular locking groove 46 in which is securely engaged a split spring locking ring 48 which engages in the seat 34 and has stop engagement with the head body 28, in opposition to the head 42, so as to preclude endwise movement of the rotor 40 in the head body.

15 20 25 The lower end 44 of the rotor 40 is formed with an axial socket 50, which can be a nut-engaging socket, but is here shown as being a preferably square socket, for removable reception of the similar cross-section stub 52 of a substantially larger nut-engaging adapter socket 54, which can be provided in different desired sizes and with differently shaped nut-receiving socket openings 56.

30 35 40 The socket rotor 40 is also the ratchet wheel component of the wrench head mechanism, since ratchet teeth 58 are formed integrally therewith. The ratchet teeth 58 are formed by indenting the rotor 40, at a location spaced between the head 42 and the socket 50. The ratchet teeth 58, as shown in FIGURES 4, 5 and 6, have flat squared outer ends 60 and are separated from each other, around the rotor, by semi-circular notches 62, which provide concavely curved sides 64 on adjacent teeth, and a concave bottom 66 between the sides 64 and continuous therewith, to have cam and sliding engagements with a ratchet dog 68.

45 50 55 The ratchet dog 68 comprises an elongated, flat, rectangular cross-section bar, of relatively heavy gauge spring material, which has an upper side edge 70 and a lower side edge 72. At the rear end of the upper edge 70 is an upstanding right angular and relatively narrow arm 74 which has on its upper end a fixed cross head or finger 76. On the lower edge 72, at a point slightly displaced from the center, toward the rear end 78 of the dog 68, is a relatively narrow, right-angular downwardly extending finger 80.

55 60 65 The head body 28 is formed internally with a ratchet dog chamber 82 which is flat and elongated and extends longitudinally of the wrench handle 14 and diametrically of the head body 28, and is parallel to and spaced from the upper end 36 of the head body 28, and is in line with the ratchet teeth 58 on the rotor 40. In an intermediate part of the bottom surface 84 of the chamber 82 is formed a centered rectangular compound recess 86 having a relatively deep rear portion 88 and a relatively shallow forward portion 90. The upper surface 92 of the recess 82 is formed, at the rear end thereof, with a slot 94, opening to the upper end 36 of the head body 28, and larger across than the ratchet dog arm 74, so as to provide for free lateral and longitudinal movements of the arm 74 in the slot 94, and to enable the dog 68 to be inserted into and removed from the chamber 82.

70 75 80 The ratchet dog 68 is loosely positioned in the chamber 82, with its finger 80 loosely engaged in the deep re-

cess portion 88, and with its arm 74 extending upwardly through the slot 94, with the finger-piece 76 above the upper end 36 of the head body 28 and extending across the slot 94.

A helical ratchet dog positioning spring 96 which is compressed between the forward wall 98 of the narrower recess portion 90 and the adjacent edge of the finger 80, with ends of the spring anchored in retaining sockets in the wall 98 and the finger, as indicated at 100 and 102, respectively. The dog 68 is of a length that its forward end 104 engages deeply in related ratchet wheel notches 62, in the erect position of the dog, with the end 104 spaced from the notch bottom 66, as shown in FIGURE 4, with the rear end 78 of the dog securely engaged in a middle retaining notch 106 which is formed intermediate the ends of the rearward end surface 108 of the chamber 82, and is spaced from left- and right-hand end retaining notches 110 and 112, respectively.

In its erect or intermediate position, shown in FIGURE 4, the ratchet dog 68 is free to have its forward end portion flexed to either side, as indicated in phantom lines, by cam engagement of related ratchet tooth sides 64 therewith, in accordance with the direction of rotation of the rotor 40, produced by swinging of the wrench handle 14 in related directions while engaged with a nut, until the forward end 104 of the dog can engage the outer end 60 of a related ratchet tooth 58 and be passed by such tooth, in a ratchet release action.

For locking the ratchet mechanism for right-hand rotation of a nut, the finger-piece 76 is moved to the extreme right, as shown in FIGURE 5, so that the dog 68 is canted toward the left, with its rear end 78 engaged in the right-hand retaining notch 112, and with its forward end 104 in stop engagement with the side 64 of a related ratchet tooth 58. The spring 76 holds the dog engaged in the retaining notch 112 and in the leftward canted position. For locking the ratchet mechanism for reverse or left-rotation of a nut, the finger-piece 76 is pushed over to the left, as shown in FIGURE 6, so that the rear end 78 of the dog 68 is engaged in the right-hand end retaining notch 10, and its forward end 104 is in stop engagement with a side of a related ratchet tooth.

With the ratchet dog 68 in either of the canted positions shown in FIGURES 5 and 6, reverse rotation of the wrench handle 14 produces cam flexing of the forward end portion of the dog by related ratchet teeth 58, in releasing ratcheting actions.

While there has been shown and described herein a preferred form of the invention, it is to be understood that the invention is not necessarily confined thereto, and that any change or changes in the structure of and in the relative arrangements of components thereof are contemplated as being within the scope of the invention as defined by the claims appended hereto.

What is claimed is:

1. A ratchet wrench head comprising a head body having an axial smooth bore extending therethrough, said body having upper and lower ends to which the bore opens, a cylindrical socket rotor journaled through said bore, means holding said rotor against endwise movement in said bore, said rotor having circumferential ratchet teeth thereon spaced from its ends, an elongated resilient dog having first and second ends, means loosely mounting the ratchet dog on the head body with the first end of the dog engaged between adjacent ratchet teeth, said means providing for canting of the dog in opposite directions, ratchet dog retaining means on said head body engaged by the second end of the dog, said retaining means comprising an intermediate notch and left- and right-hand notches positioned at opposite sides of the intermediate notch, said dog being adapted to be canted out of an intermediate radial position relative to the rotor to left- and right-hand canted positions wherein the second end of the dog is engaged in the left-hand notch or the right-hand notch, and positioning spring means compressed between the head body and the dog and yieldably urging the dog into one of these notches, and manual means for selectively canting the ratchet dog.

urging the dog into one of these notches, and manual means for selectively canting the ratchet dog.

2. A ratchet wrench head comprising a head body having an axial smooth bore extending therethrough, said body having upper and lower ends to which the bore opens, a cylindrical socket rotor journaled through said bore, means holding said rotor against endwise movement in said bore, said rotor having circumferential ratchet teeth thereon spaced from its ends, an elongated resilient dog having first and second ends, means loosely mounting the ratchet dog on the head body with the first end of the dog engaged between adjacent ratchet teeth, said means providing for canting of the dog in opposite directions, ratchet dog retaining means on said head body engaged by the second end of the dog, said retaining means comprising an intermediate notch and left- and right-hand notches positioned at opposite sides of the intermediate notch, said dog being adapted to be canted out of an intermediate radial position relative to the rotor to left- and right-hand canted positions wherein the second end of the dog is engaged in the left-hand notch or the right-hand notch, and positioning spring means compressed between the head body and the dog and yieldably urging the dog into one of these notches, and manual means for selectively canting the ratchet dog, said rotor having semi-circular cam notches separating adjacent ratchet teeth, said cam notches having concave bottoms and concave cam sides, the first end of the ratchet dog being in cam engagement with a related cam side in a canted position of the dog, said mounting means comprising an internal chamber in said head body aligned with said ratchet teeth, said chamber having a first end opening into said bore through which the first end of the ratchet dog reaches the ratchet teeth, said chamber having a closed second end on which said retaining notches are located.

3. A ratchet wrench head comprising a head body having an axial smooth bore extending therethrough, said body having upper and lower ends to which the bore opens, a cylindrical socket rotor journaled through said bore, means holding said rotor against endwise movement in said bore, said rotor having circumferential ratchet teeth thereon spaced from its ends, an elongated resilient dog having first and second ends, means loosely mounting the ratchet dog on the head body with the first end of the dog engaged between adjacent ratchet teeth, said means providing for canting of the dog in opposite directions, ratchet dog retaining means on said head body engaged by the second end of the dog, said retaining means comprising an intermediate notch and left- and right-hand notches positioned at opposite sides of the intermediate notch, said dog being adapted to be canted out of an intermediate radial position relative to the rotor to left- and right-hand canted positions wherein the second end of the dog is engaged in the left-hand notch or the right-hand notch, and positioning spring means compressed between the head body and the dog and yieldably urging the dog into one of these notches, and manual means for selectively canting the ratchet dog, said rotor having semi-circular cam notches separating adjacent ratchet teeth, said cam notches having concave bottoms and concave cam sides, the first end of the ratchet dog being in cam engagement with a related cam side in a canted position of the dog, said mounting means comprising an internal chamber in said head body aligned with said ratchet teeth, said chamber having a first end opening into said bore through which the first end of the ratchet dog reaches the ratchet teeth, said chamber having a closed second end on which said retaining notches are located.

4. A ratchet wrench head comprising a head body having an axial smooth bore extending therethrough, said body having upper and lower ends to which the bore opens, a cylindrical socket rotor journaled through said bore, means holding said rotor against endwise movement in said bore, said rotor having circumferential ratchet teeth thereon spaced from its ends, an elongated resilient dog having first and second ends, means loosely mounting the ratchet dog on the head body with the first end of the dog engaged between adjacent ratchet teeth, said means providing for canting of the dog in opposite directions, ratchet dog retaining means on said head body engaged by the second end of the dog, said retaining

means comprising an intermediate notch and left- and right-hand notches positioned at opposite sides of the intermediate notch, said dog being adapted to be canted out of an intermediate radial position relative to the rotor to left- and right-hand canted positions wherein the second end of the dog is engaged in the left-hand notch or the right-hand notch, and positioning spring means compressed between the head body and the dog and yieldably urging the dog into one of these notches, and manual means for selectively canting the ratchet dog, said rotor having semi-circular cam notches separating adjacent ratchet teeth, said cam notches having concave bottoms and concave cam sides, the first end of the ratchet dog being in cam engagement with a related cam side in a canted position of the dog, said mounting means comprising an internal chamber in said head body aligned with said ratchet teeth, said chamber having a first end opening into said bore through which the first end of the ratchet dog reaches the ratchet teeth, said chamber having a closed second end on which said retaining notches are located, said ratchet dog having a lateral arm on one edge thereof and a lateral finger on its other edge, said spring means engaging said finger at one end, said chamber having a surface provided with recess means in which said finger and said spring means are located with the other end of the spring means engaged with a part of said recess means.

5. A ratchet wrench head comprising a head body having an axial smooth bore extending therethrough, said body having upper and lower ends to which the bore opens, a cylindrical socket rotor journalled through said bore, means holding said rotor against endwise movement in said bore, said rotor having circumferential ratchet teeth thereon spaced from its ends, an elongated resilient dog having first and second ends, means loosely mounting the ratchet dog on the head body with the first end of the dog engaged between adjacent ratchet teeth, said means providing for canting of the dog in opposite directions, ratchet dog retaining means on said head body engaged by the second end of the dog, said retaining means comprising an intermediate notch and left- and right-hand notches positioned at opposite sides of the intermediate notch, said dog being adapted to be canted out of an intermediate radial position relative to the rotor to left- and right-hand canted positions wherein the second end of the dog is engaged in the left-hand notch or the right-hand notch, and positioning spring means compressed between the head body and the dog and yieldably urging the dog into one of these notches, and manual means for selectively canting the ratchet dog, said rotor having semi-circular cam notches separating adjacent ratchet teeth, said cam notches having concave bottoms and concave cam sides, the first end of the ratchet dog being in cam engagement with a related cam side in a canted position of the dog, said mounting means comprising an internal chamber in said head body aligned with said ratchet teeth, said chamber having a first end opening into said bore through which the first end of the ratchet dog reaches the ratchet teeth, said chamber having a closed second end on which said retaining notches are located, said ratchet dog having a lateral arm on one edge thereof and a lateral finger on its other edge, said spring means engaging said finger at one end, said chamber having a surface provided with recess means in which said finger and said spring means are located with the other end of the spring means engaged with a part of said recess means, said head body having a slot opening to said chamber through which said dog arm freely ex-

tends, and an enlarged finger-piece fixed on said arm outside of the head body and constituting said manual means.

6. A ratchet wrench head comprising a head body having an axial smooth bore extending therethrough, said body having upper and lower ends to which the bore opens, a cylindrical socket rotor journalled through said bore, means holding said rotor against endwise movement in said bore, said rotor having circumferential ratchet teeth thereon spaced from its ends, an elongated resilient dog having first and second ends, means loosely mounting the ratchet dog on the head body with the first end of the dog engaged between adjacent ratchet teeth, said means providing for canting of the dog in opposite directions, ratchet dog retaining means on said head body engaged by the second end of the dog, said retaining means comprising an intermediate notch and left- and right-hand notches positioned at opposite sides of the intermediate notch, said dog being adapted to be canted out of an intermediate radial position relative to the rotor to left- and right-hand canted positions wherein the second end of the dog is engaged in the left-hand notch or the right-hand notch, and positioning spring means compressed between the head body and the dog and yieldably urging the dog into one of these notches, and manual means for selectively canting the ratchet dog, said rotor having an end formed with an axial polygonal socket.

7. A ratchet wrench head comprising a head body having an axial smooth bore extending therethrough, said body having upper and lower ends to which the bore opens, a cylindrical socket rotor journalled through said bore, means holding said rotor against endwise movement in said bore, said rotor having circumferential ratchet teeth thereon spaced from its ends, an elongated resilient dog having first and second ends, means loosely mounting the ratchet dog on the head body with the first end of the dog engaged between adjacent ratchet teeth, said means providing for canting of the dog in opposite directions, ratchet dog retaining means on said head body engaged by the second end of the dog, said retaining means comprising an intermediate notch and left- and right-hand notches positioned at opposite sides of the intermediate notch, said dog being adapted to be canted out of an intermediate radial position relative to the rotor to left- and right-hand canted positions wherein the second end of the dog is engaged in the left-hand notch or the right-hand notch, and positioning spring means compressed between the head body and the dog and yieldably urging the dog into one of these notches, and manual means for selectively canting the ratchet dog, said rotor having an end formed with an axial polygonal socket, and an interchangeable adapter nut socket having a polygonal stud removably engaged in said socket.
